US00D780115S

(12) **United States Design Patent** (10) **Patent No.:** **US D780,115 S**
(45) **Date of Patent:** **** Feb. 28, 2017**

(54) **CHARGER**

(71) Applicant: **Microsoft Mobile Oy**, Espoo (FI)

(72) Inventor: **Chao Huang**, Espoo (FI)

(**) Term: **15 Years**

(21) Appl. No.: **29/549,302**

(22) Filed: **Dec. 21, 2015**

Related U.S. Application Data

(62) Division of application No. 29/470,103, filed on Oct. 17, 2013, now Pat. No. Des. 749,044.

(51) **LOC (10) Cl.** **13-02**

(52) **U.S. Cl.**

USPC **D13/107**

(57) **CLAIM**

The ornamental design for a charger, as shown and described.

DESCRIPTION

FIG. 1 is a perspective front view of a charger showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate portions of the charger that form no part of the claimed design.

1 Claim, 4 Drawing Sheets
